UNITED STATES PATENT OFFICE

110,738

DESIGN FOR AN IGNITION TRANSFORMER

Joseph G. Sola, Oak Park, Ill., assignor to Sola
Electric Co., Chicago, Ill., a corporation of
Delaware

Application January 15, 1937, Serial No. 67,073

Term of patent 7 years

To all whom it may concern:

Be it known that I, Joseph G. Sola, a citizen
of the Argentine Republic, residing at Oak Park,
in the county of Cook and State of Illinois, have
invented a new, original, and ornamental Design
for an Ignition Transformer, of which the fol-
lowing is a specification, reference being had to
the accompanying drawing, forming part thereof.

In the drawing,—

Fig. 1 is a side elevational view of an ignition
transformer embodying my design;

Fig. 2 is a top plan view of the transformer;
and

Fig. 3 is a bottom plan view of the transformer.

The dominant features of my design include a
vertically disposed cylindrical casing provided at
its top with a centrally disposed circular flat por-
tion the margin of which is connected to the side

walls of the casing by a convexed portion; a thin
flat closure plate for the bottom of the casing the
edges of which coincide with the side walls of
the casing except at two opposite places where
the edges of the plate project outwardly in tri-
angular shaped portions which are slotted; two
tapered posts projecting downwardly from a com-
mon base attached to the under side of said clo-
sure plate, each of said posts terminating in op-
posite disposed recesses; and a bushing pro-
jecting from one side of the casing a distance
above the bottom of the closure plate approxi-
mately equal to its diameter.

I claim:—

The ornamental design for an ignition trans-
former, substantially as shown and described.

JOSEPH G. SOLA.
